UNITED STATES PATENT OFFICE

2,200,493

HEIGHT INCREASING SHOE

Amelia Ehrich, New York, N. Y.

Application September 2, 1938, Serial No. 228,085

3 Claims. (Cl. 36—8.5)

This invention relates to new and useful improvements in a height increasing shoe.

The invention has for an object the construction of a shoe in which padding material is arranged in the heel portion thereof in a particular manner so as to increase the apparent height of a person wearing the shoe to give the wearer apparent added stature and simultaneously tilt the body of the wearer forward on the ball of the foot. In conjunction with the pad it is proposed to increase the height of the back portion of the shoe upper so that the shoe may be properly engaged on the foot even though there is the addition of the pad therein.

More specifically, the invention proposes the provision of a pad of cork or other suitable material interposed between the inner sole and the outer sole for accomplishing the height increasing feature previously referred to.

As another object of this invention it is proposed to construct a pad in various ways to accomplish the same result.

Still further the invention contemplates the use of an adjusting means by which the height of the pad may be controlled.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a shoe constructed according to this invention and illustrated with a side portion thereof broken away to show the interior pad in section.

Fig. 2 is a perspective view of the inner sole, per se, shown with the pad attached.

Fig. 3 is a fragmentary elevational view of a shoe constructed according to a modification of this invention, a portion thereof being broken away to disclose interior parts.

Fig. 4 is a plan view of the inner sole and the pad beneath the sole, illustrated per se.

Fig. 5 is a vertical sectional view taken on the line 5—5 of Fig. 3.

Fig. 6 is a fragmentary side elevational view of another shoe constructed according to a still further embodiment of this invention, a portion thereof being broken away to disclose interior parts.

Fig. 7 is a vertical sectional view, taken on the line 7—7 of Fig. 6.

Fig. 8 is a fragmentary rear view of Fig. 6, looking in the direction of the arrows 8—8.

Fig. 9 is a sectional view taken on the line 9—9 of Fig. 8.

The height increasing shoe, according to this invention, includes a shoe upper 10 mounted upon an outer sole 11 and heel 12. An inner sole 13 is disposed within the shoe upper. A pad 14 is interposed between the inner and outer soles and extends from the arch area of the shoe to the heel, and increases gradually in thickness to the rear edge of the heel. The shoe upper 10 is constructed of additional height, so that there is sufficient room between the upper face of the inner sole 13 and the top edge of the upper to properly secure the shoe upon the foot. The dot and dash lines A indicate the normal height of a shoe upper of the particular type of shoe illustrated. The extra material above the line A indicates the additional material of the shoe upper needed according to this invention.

The pad 14 preferably should be constructed of cork but may be of any other suitable material. It is advisable that the pad 14 be permanently attached to the lower face of the inner sole 13 as clearly shown in Fig. 2. This may be accomplished with glue or other cementing material, or by sewing.

The shoe when worn gives the appearance of a conventional shoe. The advantage of the pad construction resides in the fact that a person's apparent height may be increased by the use of this shoe. This is achieved because of the extra thickness of the pad 14. It should be noted that the pad 14 is disposed within the shoe and therefore does not add to the height of the heel 12.

In Figs. 3 and 5 inclusive a modified form of the invention has been disclosed which distinguishes from the prior form in the construction of the pad. According to this form of the invention the shoe is provided with a pad consisting of a relatively thin pad 24 of cork or other suitable material secured to the bottom face of the inner sole 13, and a metallic or other frame 25 interposed between the bottom of the pad 24 and the outer sole 11 of the shoe. This frame 25 consists of superimposed horizontal U-shaped arms 25^a and 25^b held in relatively spaced positions by brace portions 25^c. Because of the hollow construction of the frame or other suitable light material, the shoe will not be unduly heavy. The cork or other suitable pad 24 comprises a sufficient cushion so that the frame 25 is not annoying when the shoe is worn.

In Figs. 6 and 7 another modified form of the

invention has been disclosed which distinguishes from the prior forms also in the construction of the pad. According to this form there is a relatively thin pad of cork or other suitable material 5 34 attached to the bottom face of the inner sole 13. A thin metallic plate 35 is secured to the bottom face of the pad 34 at the heel area. This plate 35 is formed with a groove 36. A slide 37 is slidably mounted in this groove. This slide 37 is 10 pivotally connected with a lug 38 mounted upon the top of a tubular member 39. This tubular member extends downwards and is formed with internal threads. A screw 40 is rotatively supported in a bracket 41 mounted upon the bottom face of the heel 12. This screw 40 threadedly engages the tubular member 39.

The height of the padded portion of the shoe may be varied to suit one's comfort by turning the screw 40. This may be accomplished by the 20 use of a screw driver engaging the slotted headed end of the screw. When the screw 40 is turned in one direction it will cause the tubular member 39 to move in one direction, for example to increase the thickness of the padded portion of the 25 shoe. The screw may be turned in the other direction to decrease the padded portion.

The shoe upper 10, may be provided with a semi-elastic insert 10^a, consisting of a thinned sheet of leather 42 and an elastic backing sheet 30 43, cemented or otherwise adhered to the thinned leather sheet 42. The semi-elastic insert is stitched as at 44 or otherwise secured to the upper rear edge of the shoe upper 10, to form a yielding arrangement which permits the shoe to snugly 35 hug the foot, also to facilitate the pulling of the shoe on, and removal of the shoe from the wearer's foot. Continued wearing of the shoe causes the leather in the counter portion to become stretched forming a gap between the counter portion 40 of the shoe and the heel of the foot which is taken up by the elastic insert causing the counter portion of the shoe to snugly fit the foot. This insert may also be located at any other portion of the shoe upper. It is to be understood that the 45 padding may be of any suitable material, such as cork, rubber, felt, etc. Also that the shoe may be used without any semi-elastic insert whatsoever.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a shoe having a heel, an inner sole, and an outer sole, a pad interposed between said soles in the vicinity of said heel and having its front end secured in position and its rear end free and spaced from said outer sole to be moved upwards

and downwards about the secured point as a pivot to correspondingly move and support said inner sole, a plate fixedly mounted on the bottom face of said pad adjacent the rear end thereof, a tubular member extending substantially at right angles to said pad and located below said plate, means in said heel for moving said tubular member vertically upwards and downwards and a slide pivotally mounted on the top end of said tubular member and engaging a groove formed in the bottom face of said plate for connecting said tubular member to said plate so that as said tubular member moves vertically upwards and downwards said slide slides relative to said plate to correspondingly move the free rear end of said pad.

2. In a shoe having a heel, an inner sole, and an outer sole, a pad interposed between said soles in the vicinity of said heel and having its front end secured in position and its rear end free and spaced from said outer sole to be moved upwards and downwards about the secured point as a pivot to correspondingly move and support said inner sole, a plate fixedly mounted on the bottom face of said pad adjacent the rear end thereof, a tubular member extending substantially at right angles to said pad and located below said plate, means in said heel for moving said tubular member vertically upwards and downwards and a slide pivotally mounted on the top end of said tubular member and engaging a groove formed in the bottom face of said plate for connecting said tubular member to said plate so that as said tubular member moves vertically upwards and downwards said slide slides relative to said plate to correspondingly move the free rear end of said pad.

3. In a shoe having a heel, an inner sole, and an outer sole, a pad interposed between said soles in the vicinity of said heel and having its front end secured in position and its rear end free and spaced from said outer sole to be moved upwards and downwards about the secured point as a pivot to correspondingly move and support said inner sole, a plate fixedly mounted on the bottom face of said pad adjacent the rear end thereof, a tubular member extending substantially at right angles to said pad and located below said plate, means in said heel for moving said tubular member vertically upwards and downwards and a slide pivotally mounted on the top end of said tubular member and engaging a groove formed in the bottom face of said plate for connecting said tubular member to said plate so that as said tubular member moves vertically upwards and downwards said slide slides relative to said plate to correspondingly move the free rear end of said pad, said groove being extended parallel to the length of said shoe.

4. In a shoe having a heel, an inner sole, and an outer sole, a pad interposed between said soles in the vicinity of said heel and having its front end secured in position and its rear end free and spaced from said outer sole to be moved upwards and downwards about the secured point as a pivot to correspondingly move and support said inner sole, a plate fixedly mounted on the bottom face of said pad adjacent the rear end thereof, a tubular member extending substantially at right angles to said pad and located below said plate, means in said heel for moving said tubular member vertically upwards and downwards and a slide pivotally mounted on the top end of said tubular member and engaging a groove formed in the bottom face of said plate for connecting said tubular member to said plate so that as said tubular member moves vertically upwards and downwards said slide slides relative to said plate to correspondingly move the free rear end of said pad, said means comprising a screw having its head rotatively supported in said heel and its shank portion threadedly engaged into said tubular member.

AMELIA EHRICH.
